UNITED STATES PATENT OFFICE.

WILLIAM L. HEWES, OF SPRINGFIELD, MASSACHUSETTS.

SIGNALING DEVICE FOR AUTOMOBILES.

1,391,830.

Specification of Letters Patent. Patented Sept. 27, 1921.

Application filed July 24, 1920. Serial No. 398,718.

To all whom it may concern:

Be it known that I, WILLIAM L. HEWES, a citizen of the United States, residing in the city of Springfield, in the county of 5 Hampden and State of Massachusetts, have invented certain new and useful Improvements in Signaling Devices for Automobiles, whereof the following is a specification, reference being had to the accompanying drawings.

The object of the invention is to make it possible for the driver of an automobile or other vehicle to communicate to a traffic officer at a street intersection, the direction 15 in which he intends to proceed. With this end in view, I have devised a signaling device designed to be attached to the wind shield of an automobile, and which is capable of being set to indicate the direction 20 intended to be traveled.

Among the advantages I attain by my invention are ease of attachment without necessitating the aid of any special securing means; simplicity of operation; cheapness 25 of manufacture; and extreme durability in use.

Other advantages of my invention will become apparent from the detailed description which follows.

30 In the drawings, Figure I is a fragmentary elevation of the inside of a wind shield of an automobile with a convenient embodiment of my invention attached thereto, the slidable signaling member shown, being in 35 its normal or neutral position.

Fig. II is a cross sectional view along the plane of the arrows II—II in Fig. I; and

Fig. III is an illustration similar to Fig. I showing the signaling member in one of 40 its shifted positions.

As herein represented, the device comprises a mounting plate 1 having at its ends perpendicular extensions 2, 2, which are bent over at their tops as at 3, 3, to form straps 45 by which the device may be hung in a horizontal position from the top edge of the lower section 4 of the wind shield of the automobile. In this location, it will be apparent that the device is conveniently accessible to the driver and may be readily seen through the glass of the wind shield by the traffic officer. On the back of the plate 1 is mounted a signaling member 5 which is 50 slidably supported between a pair of co-operative central, integral tabs 6, 6, offset from the center of said plate 1 whereby it is

both retained and guided. Said plate 1 and the signaling member 5 are respectively ridged longitudinally as at 7, 8, to afford a tongue and groove connection by which the 60 signaling member is guided in its motion. As shown, the member 5 has at its extremities arrow heads 9 and 10 adapted to be selectively displayed beyond opposite ends of the mounting plate to indicate the intended 65 direction of travel. The arrow heads 9, 10 are respectively formed with abrupt shoulders 11, 12, which engage alternatively with the corresponding side edges of the tabs 6, 6, to limit the motion of the signaling member 70 when the latter is shifted either to the right or to the left, as the case may be. At its center, the signaling member 5 is provided with a finger grasp in the form of a pair of outstanding punched projections 75 13, 13.

In practice, it will be seen that when reaching a street intersection, the driver may readily communicate to the traffic officer the direction in which he intends to proceed by 80 simply shifting the signaling member either to the right or left, thereby displaying one or the other of the arrow heads beyond the corresponding end of the mounting plate 1. If the intention is to proceed straight ahead, 85 the signaling member of the device is left in the normal or neutral position as shown in Fig. I.

Having thus described my invention, I 90 claim:

1. A device of the character described comprising a mounting plate with integral offset-tabs at the rear thereof, toward the driver, and a signaling member slidably supported between said tabs and having at its 95 extremities arrow heads adapted to be selectively displayed beyond opposite ends of the mounting plate to indicate the intended direction of travel.

2. A device of the character described 100 comprising a mounting plate, and a signaling member slidably supported at the rear of the mounting plate toward the driver and provided at its extremities with arrow heads adapted to be selectively displayed beyond 105 opposite ends of the mounting plate to indicate the intended direction of travel, said plate and signaling member being ridged longitudinally to form a registering tongue and groove for the guidance of the signaling 110 member.

3. A device of the character described

comprising a mounting plate with a pair of integral retaining tabs offset at the center of its rear side, toward the driver, and a signal member slidably supported between said tabs and having at its ends arrow heads adapted to be selectively displayed beyond opposite ends of the mounting plate to indicate the intended direction of travel, the extent of projection of the signaling member in either 10 instance being limited by engagement of a shoulder of one of the other of the arrow heads with the corresponding side edges of the retaining tabs of the mounting plate.

4. A device of the character described 15 comprising a mounting plate with means for mounting it at the rear of the wind shield of an automobile, toward the driver overhanging guide and retaining means outstanding rearward from said plate at the center thereof, and a signaling member at the rear of said 20 plate slidable in said guide means so that

either end thereof may be projected beyond the corresponding end of the plate to an extent limited by engagement of the other end thereof with said guide means.

5. A device of the character described comprising a mounting plate with means for mounting it at the rear of the wind shield of an automobile, toward the driver; guide and retaining tabs offset rearward from said plate at the center thereof; and a signaling member at the rear of said plate slidable between said tabs, and having a tongue and groove engagement with said plate for guiding it in its longitudinal movement.

In testimony whereof, I have hereunto signed my name at Springfield, Massachusetts this 19th day of July, 1920.

WILLIAM L. HEWES.
